United States Patent Office.

JAMES L. NELSON, OF LEWISBURG, WEST VIRGINIA.

Letters Patent No. 93,550, dated August 10, 1869.

IMPROVEMENT IN CHURNS.

The Schedule referred to in these Letters Patent and making part of the same.

To all whom it may concern:

Be it known that I, JAMES L. NELSON, of Lewisburg, in the county of Greenbrier, and State of West Virginia, have invented new and useful Improvements in Churns; and I do hereby declare that the following is a full, clear, and exact description thereof, reference being had to the accompanying drawings and letters, that form a part of this specification, and in which—

Figure 1 represents a side elevation of my improved churn-power, and

Figure 2, a plan view of the same.

Similar letters indicate like parts in both figures.

My invention relates to improvements in churn powers; and to this end,

It consists in securing the balance-wheel on the opposite side of the bench from the lever, thereby lessening the friction.

It further consists in the employment of a movable crank on the shaft-end, whereby any desired stroke may be obtained.

To enable others skilled in the art to which my invention appertains, to make and use the same, I will now describe its construction and operation.

In the accompanying drawing—

A represents the bench.

a a, the legs of the same.

b b represent boxes, secured on the upper side of the bench A. In these boxes works the shaft B, which is

provided, at one end, with the balance-wheel C, said wheel being provided with an arm, *d*, for operating the machine.

On the other end of the shaft B is attached the crank D, provided with three or more holes, *e e*, for the purpose of regulating the stroke. The lower arm of this crank works into the slotted end of the lever G, which is pivoted at its rear end to the pin or projection *g*, formed on the side of the bench.

h is a spring, one end of which is secured to the lever G, and the other end bent, as seen in fig. 2, and passed through a hole in the centre of the lever.

n is a metal band, into which the dasher is passed, and is retained in place by means of the spring *h* passing through the dasher and the band.

Having thus described my invention,

What I claim as new, and desire to secure by Letters Patent, is—

The combination of the balance-wheel C, shaft B, adjustable crank D, slotted lever G, and spring *h*, with the bench A, all arranged to operate substantially as herein shown and described.

In testimony that I claim the foregoing as my own, I affix my signature, in presence of two witnesses.

JAMES L. NELSON.
